DINER

Bertron G. Harley, Saco, Maine

Application May 24, 1935, Serial No. 23,147

13 Claims. (Cl. 20—2)

This invention relates to portable restaurants known as diners and to building structure peculiarly adapted for housing the same and analogous structures and is an improvement on the 5 portable sectional diner shown and described in an application filed by me June 4, 1934, Serial No. 728,897.

The object of the present invention is to cheapen the construction shown and described in 10 the aforesaid application and to provide a sectional diner structure less expensive to build and which will require considerable less time in the erection of a diner.

A further object of the invention is to improve 15 the means for detachably securing the sections of the diner together and to provide simple practical and comparatively inexpensive means for this purpose adapted also to effectively seal the joints between the diner sections without interfering with the ready separation of the sections 20 of the diner when it is desired to rearrange the same.

Another object of the invention is to provide a 25 sectional diner composed of transversely disposed diner sections having separable floor, side wall, and roof portions or sections and provided at the joints between the diner sections with steel channel bars extending between the floor and roof portions or sections and tying the roof and floor 30 portions together so firmly that the side walls can neither buckle nor bulge and neither slew over nor separate from one another or from the floor and roof portions.

Another object of the invention is to provide a 35 sectional diner of this character in which the floor, side wall, and roof portions or sections when assembled will be so rigidly put together and reinforced and the roof and floor portions so securely tied together that the diner although composed of separable diner sections may be moved 40 about as a unit without causing separation of the diner sections or any of the parts thereof.

Another object of the invention is to provide a 45 sectional diner in which the steel channel bars for tying the floor and roof sections together will lock the tenons of the wall studs in place so securely that they cannot possibly slip out of the mortises or recesses provided for the said tenons.

It is also an object of the invention to provide 50 simple and effective means for rendering the sectional diner thoroughly weatherproof at the junction of the side wall and roof portions.

An important object of the present improvements 55 is to render possible the preserving of all or the major portions of an original building

structure while enabling certain encompassing housing sections which go to make up the length of the diner to be interchangeable in their relative positions lengthwise of the diner when it is desired to enlarge the diner and remove the same 5 from one location to another or rearrange or modernize its contained restaurant equipment.

A further object of the invention is to enable 10 the roof part of one of the encompassing sections to be interchanged selectively with the roof part 10 of a different encompassing section and likewise to enable the side wall sections and the floor sections of any encompassing diner section to be interchanged with the wall and floor portions of a different section. In this way, the relative positions of blank wall spaces, windows, doors, 15 chimneys, exhaust fan apertures, plumbing pipes, etc. may be changed at will without destroying and throwing away or requiring reconstruction of an old roof, floor or wall portion of a building with 20 which the built-in restaurant equipment has been structurally associated.

A further object of the invention is to provide 25 improved means for detachably joining separable diner sections so as to enable the sections 25 to be taken apart as individual units and secured together again either in the same or in different relationship without requiring an extremely accurate lining up of the sections as is necessary 30 where separate holes for tie bolts or the like must 30 be brought into precise registering relation before the sections can be secured together. The improved joiner means includes vertically arranged spline members operating in vertical 35 channels of the adjacent portions of the diner 35 sections and adapted to relieve of excessive stress lag screws employed for maintaining the spline members in clamping frictional engagement with the side wall sections of the diner. This structure also permits the taking apart and reassembling 40 of the diner sections with minimum damage to the painted surfaces of the sections and room is afforded for expansion or shrinkage of the sections without development of stresses 45 which would cause warping.

A still further object of the invention is to provide 50 a separable and detachable structure of this character which will not interfere with the use of the ventilating means shown and described in the aforesaid application and in a divisional application filed by me the 24th day of May, 1935, Serial No. 23,146.

The advantages of the present improvements 55 stand out in relation to serious problems which have come to confront the manufacturers and

operators of wayside diners. The early lunch cart was not much more than a wagon on wheels constructed in long and narrow proportions. This characteristic of shape has been maintained 5 in the modern and more spacious diners partly because of the greater ease with which one or two attendants can quickly serve meals at a long straight bar or counter. Such bar or counter requires a complement of kitchen appliances and 10 food preparing stations arranged in a long row paralleling the counter and extending along a substantial portion of the length of the diner and usually erected against the long rear wall of the diner housing. Kitchen equipment such as the 15 coffee urn with its fuel supply and drain pipes, the gas stove with its fume gathering hood and outlet chimney, the hot plate with its smoke removing vent and forced draft exhaust fan require structural association with that portion of the 20 housing in which they are located. Consequently such pieces of equipment cannot be separated from the housing without disrupting the latter and leaving an unsightly condition requiring costly reconditioning or reconstruction to remedy. 25

Nevertheless, there is almost always desired a relocation of the component parts of the equipment when a diner is removed to a new location or its length increased to accommodate business 30 growth. The location of doors and windows is seldom suited to the new condition either of changed equipment or exterior surroundings. Heretofore it has been necessary to waste a large portion of the owner's initial investment in the 35 diner in making the required changes. The remedy for these conditions provided by the present invention also affords relief from the restrictions set up by the laws of many states against the use of the highways for transporting a wheeled load 40 of such large dimensions as the modern integral diner building.

With these and other objects in view, the invention consists in the construction and novel combination and arrangement of parts herein- 45 after fully described, illustrated in the accompanying drawings and pointed out in the claims hereto appended, it being understood that various changes in the form, proportions and minor details of construction may be resorted to without departing from the spirit or sacrificing any 50 of the advantages of the invention.

In the drawings:

Figure 1 is a view of my improved diner in front elevation showing in full lines a small diner composed of few sections and embodying the present 55 improvements and showing in broken lines the modified appearance of the diner when its length is increased by the addition of interchangeable encompassing sections.

Figure 2 is a diagrammatic floor plan suggesting one possible interior arrangement for the elongated diner of Figure 1.

Figure 3 is a front perspective view of one 65 encompassing end section, the interior equipment of which is indicated by broken lines.

Figure 4 is a view similar to Figure 3 showing an intermediate encompassing section.

Figure 5 is a view similar to Figure 4 showing another intermediate encompassing section.

Figure 6 is a view similar to Figure 3 showing the exterior of the other encompassing end section. 70

Figure 7 is an enlarged view looking lengthwise of the diner and is taken partly in section on the 75 plane 7—7 of Figure 1.

Figure 8 is an enlarged vertical sectional view through one side of one of the diner sections showing the side wall section and portions of the floor section and the roof section. 5

Figure 9 is an enlarged detail horizontal sec- 10 tional view taken substantially on the line 9—9 of Figure 1.

Figure 10 is a detail perspective view illustrating the construction of the side sills and joists. 15

Figure 11 is a detail perspective view of portions of certain parts of one of the diner sections and showing the said parts separated and illustrating the precise manner of assembly. 20

Figure 12 is an enlarged horizontal sectional view illustrating the arrangement of the corner 25 structure of the diner.

Figure 13 is a rear perspective view of certain 30 encompassing diner sections joined together and drawn on a somewhat larger scale than Figs. 3 to 6 inclusive, the wall portion of one of the sections being omitted.

A typical layout for a modern diner interior with its fittings and restaurant equipment is indicated in Figure 2. A long bar or service counter 10 is flanked by a row of stool seats 11. In a 25 small diner this counter and row of seats may occupy nearly the entire length of the interior whereas in larger diners they may occupy only a portion of the diner's length. Additional serving capacity is represented by tables 12 and seats 30 13 which are sometimes replaced by a second long counter paralleling the main counter 10.

Extending along the rear wall of the diner a series or row of food preparing stations is dia- 35 grammatically represented and may comprise from left to right a work bench 14 with light 40 from window 15, a stove or hot plate 16, a coffee urn 17, an ice cream station 18, a draft beer station 19, a dish washing sink 20 and a food refrigerator 21. Most of the foregoing stations do 45 not require windows. Continuing to the right are two booth tables 22 with their seats 23, lounge 50 seats 24, lavatories 25, each preferably having window light. Any other desired arrangement may, of course, be employed and as the particu- 55 lar construction of the fittings and restaurant 60 equipment does not constitute a portion of the present invention and are fully described and illustrated in the said applications further description of the same in the present application 65 is deemed unnecessary. It will be evident that 70 in changing the arrangement of the equipment of a diner as heretofore constructed, the owner must leave the various pieces of kitchen equipment at their original locations in the length of the diner 75 or disrupt major portions of the diner housing construction.

As a solution to these problems, the present invention contemplates a building structure for 80 housing diners composed of a number of separable encompassing housing or diner sections which is possible because of the considerable 85 length of a diner in comparison with its trans- 90 verse dimensions. The separable relationship of these housing sections is illustrated in Figures 3 to 6 inclusive. Each housing or building section 95 comprises in its construction a floor section 26, wall sections 27 and a roof section 28. The floor 100 section comprises tongue and groove flooring 29 laid on transverse joists 30 provided at their 105 ends with tenons 31 which are fitted in mortises 32 of side sills 33. The side sills may constitute 110 a portion of the floor section or be continuous and extend from and be associated with a plu- 115 rality of housing sections. The tenons 31 which 120

are located at the ends of the joists have their upper edges flush with the upper edges or faces of the joists and the mortises 32 are of greater depth than the tenons 31 and extend above the same when the tenons 31 are seated in the mortises as clearly illustrated in Figure 10 of the drawings. The upper portions of the mortises above the tenons 31 form recesses for bottom tenons 34 of side wall studs 35 to provide foot locks 10 for the side wall sections 27.

The side wall sections are composed of the vertical studs 35 and inner and outer covering sheets 36 and 37 suitably secured to the studs. The inner sheet 36 which preferably consists of 15 insulating wall board extends from the floor to the roof section and the outer sheet 37 which is preferably sheet metal extends above and below the upper and lower ends of the studs to provide upper and lower extensions 38 and 39. The lower 20 extension 38 overlaps the side sill 33 at the outer side face thereof and fits in a recess 38a in the upper outer corner of the sills of the same.

Each side wall section is provided at the top with a side wall plate 41 approximately L-shaped 25 in cross-section and provided in its lower face with mortises 42 which receive upper tenons 43 located at the central portions of the upper ends of the side wall studs. By this construction a head lock is formed for the side wall sections. 30 The L-shaped formation of the side wall plate provides a longitudinal recess 44 at the inner upper portion of the side wall plate 41 to receive a depending portion of a roof plate 45 which is inverted L-shaped in cross-section forming a longitudinal recess at its lower outer portion as clearly illustrated in Figure 8 of the drawings. The plate 41 of the side wall section and the roof plate 45 are fitted together to interlock the roof section against lateral movement and the top extension 38 of the outer covering sheet 37 of the side wall section extending upwardly over the outer face of the side wall plate 41 and projects above the same and overlaps slightly the adjacent portion of the roof plate. The extensions 38 may 40 be integral with the outer covering sheet or otherwise formed. The said top extension 38 is secured to the said plates 41 and 45 by top lag bolts 46 which pierce the top portion or extension 38 of the outer covering sheet 37 and the upper portion 45 of the side wall plate and its inner end portion pierces the roof plate 45 and an inner face plate 45a whereby the roof section and the side wall section are tied together.

The inner face plate 45a which preferably consists of a thin metal strip or plate covers the joint between the continuous side wall plate 41 and the roof plate 45 and assists in assembling and centering the roof plate 45. The inner face plate 45a forms a wall for the recess of the continuous side wall plate 41 and cooperates with the same to provide a groove or channel into which the depending portion of the roof plate may be readily fitted. The side wall plate 41 while preferably continuous throughout the entire length 60 of the diner may be otherwise constructed.

The roof section 28 consists of a roof covering 47 of sheet metal or other suitable material and roof ribs 48 to which the roof covering 47 is secured. The roof ribs 48 are provided at their ends 70 with recesses 49 cut into the terminal portions of the roof ribs at the lower edges or faces thereof to enable the ends of the roof ribs to rest upon the upper faces of the roof plates 45 and to fit against the inner side faces thereof.

75 The roof ribs may be secured to the roof plates

48 in any suitable manner and the roof sections are provided with horizontal bead strips 50 located at the ends of the roof ribs and fitting against the same and against the adjacent portions of the roof plates and the side edges of 5 the roof covering 47 and provided in their lower edges or faces with recesses 51 which receive and conceal the upper edge of the outer covering sheet 37. The upper portion 52 of the inner sheet extends beyond the upper ends of the studs 10 35 to the roof ribs to form an upper extension which overlaps the side section plate 41 and a portion of the roof plate 45. While the outer covering sheets of the side wall sections and the roof covering are described as being preferably 15 composed of sheet metal and the inner covering sheet of the side wall section is preferably insulating wall board, any other suitable material may, of course, be employed as will be readily understood. The advantages, however, of employing sheet metal exteriorly of the diner or analogous structure of this character and the insulating wall board interiorly thereof will be apparent. The inner and outer covering sheets 36 and 37 are spaced apart by the vertical side 20 wall studs 35 and dead air insulating spaces are thereby provided in the side wall portions of the 25 diner.

The end studs of the side walls of the housing or building sections are provided with vertical channels 53 extending from the floor section to the side wall plate and the adjacent channels 53 receive spline members 54 of wood or metal which seal the joints between the housing or building sections and also space the adjacent end studs from each other to provide an intervening space 55 for lag bolts 56. The space also allows for contraction and expansion and enables the lag bolts to extend from the exterior of the side wall sections to the spline member without piercing any 30 portion of the side wall sections. The joint is bridged and concealed at the exterior of the housing sections by a steel channel joint cover bar 57 which is pierced at intervals by the lag 35 bolts and the latter extend inwardly from the channel joint cover to the spline member 54 and are preferably provided at their outer ends with polygonal heads 58 to enable them to be engaged by a wrench or other tool for tightening the lag bolts and drawing the spline members into tight 40 frictional or clamping engagement with the end studs whereby the housing sections are securely 45 and detachably tied or connected together and the joint securely sealed from the roof section to the floor section. The vertical side edges of 50 the outer covering sheets 37 are preferably bent outwardly to form flanges 59 which are located within the channel of the joint cover. The side wall sections are also preferably provided at their inner faces with a joint cover strip 60 of wood 55 or any other suitable material and preferably a molding of an ornamental character. The inner joint cover strip may be secured to the side wall sections by any suitable means. The top molding 60 extends down over the upper ends of the steel channels and provides a weather-tight joint 65 at juncture of the roof portions or sections and the side wall portions or sections. The channel bars may if desired be arranged interiorly of 70 the wall sections.

While the spline members preferably extend from the roof section to the floor section for completely sealing the joint between the sections they may, of course, be of any desired length and owing 75 to the vertical arrangement of the spline member

54 and the channels which receive the same any sagging of the sections will not affect the coupling or interlocking relation between the spline member and the side wall sections or affect the 5 tying of the wall sections together or the adjustment afforded by the lag bolts which may be readily tightened if required. The spline section and the adjusting bolts will enable the housing sections to be easily and quickly assembled and 10 readily separated without injury to the housing sections which may be readily reassembled and rearranged as desired.

Where the edges of two wall sections are to be assembled in right-angular relation a corner post 15 64 is employed and arranged as illustrated in Figure 12 of the drawings. The corner post 64 which is preferably rounded at the exterior corner is provided in two of its adjacent faces with vertical channels 65 similar to the channels 53 of the 20 adjacent end studs of the said wall sections and receiving a spline 66. The splines 66 which join or tie the corner post 64 to the adjacent wall sections are arranged in the channels 65 of the corner post and in the channels 53 of the said 25 wall sections and tie or connect the corner post 64 and the wall sections together. The splines 66 which may be of either metal or wood space the corner post from the adjacent end studs of the wall sections to provide intervening spaces 30 for lag bolts 67 which extend from steel channel bars to the splines 66.

The lag bolts 67 pierce the channel bars 68 and 35 pierce and engage the splines 66 for maintaining the same in tight frictional engagement with the walls of the channels or grooves of the corner post and the adjacent end studs. The exterior faces of the corner post are preferably covered by a sheet metal covering plate 69 having its 40 marginal side portions overlapped by the channel bars 68. The side edges of the corner post covering sheet are preferably bent at right angles to form flanges 70 which are arranged in the channels of the steel channel bars 67.

The lower ends of the channel bars 57 are tied 45 to the side sills by lower lag bolts 40 and the upper ends of the channel bars 57 are tied to the roof sections by the upper lag bolts 46 which extend through the roof plates 45 and the continuous side plates 41, thereby tying the roof and floor 50 sections together. The vertical steel channel bars 57 which are arranged at regular intervals form a steel cage for the diner extending from the floor sections to the roof sections and tying the roof and floor sections together so firmly that the 55 side wall sections can neither buckle nor bulge and can neither slew over nor separate from one another or from the roof and floor sections. Also the steel cage locks the tenons 43 of the side wall studs so securely in place that they cannot slip 60 out of the mortises or recesses in which they are arranged. The diner even though made in sections, when assembled is so rigidly put together and reinforced that it can be moved about as a unit.

65 The housing or building sections are designed to be provided with clear stories 61 having windows 62 and transoms 63 to afford the desired 70 ventilating means. As the ventilating means and the operating mechanism therefor are fully shown and described in the aforesaid applications and do not constitute a portion of the improvements of the present invention, further description thereof is deemed unnecessary.

What is claimed is:

75 1. A sectional building construction for diners

and the like including a plurality of separate transversely disposed housing sections comprising a floor section, side wall sections having vertical end studs provided with longitudinal channels, a roof section supported by the side wall 5 sections, and means for detachably securing the transverse housing sections together comprising a vertical spline member fitted in the channels of the adjacent end studs and adjustable means connected with the spline member for frictionally 10 engaging the same with the said end studs.

2. A sectional building construction for diners and the like including a plurality of separate transversely disposed housing sections comprising a floor section, side wall sections having vertical end studs provided with longitudinal channels, a roof section supported by the side wall 15 sections, and means for detachably securing the transverse housing sections together comprising a vertical spline member fitted in the channels 20 of the adjacent end studs and adjustable means connected with the spline member for frictionally engaging the same with the said end studs, said spline member being of sufficient size to space the engaged end studs from each other to provide 25 an intervening space for the said adjusting means and for contraction and expansion of the side wall sections.

3. A sectional building construction for diners and the like including a plurality of separate 30 transversely disposed housing sections composed of a floor section, side wall sections having vertical end studs provided with longitudinal channels, a roof section supported by the side wall sections, and means for detachably securing the 35 transverse housing sections together comprising a vertical spline member fitted in the channels of the end studs, a channel joint cover bridging the joint between the housing sections and a lag bolt piercing the channel joint cover and engaging the spline member for frictionally 40 engaging the latter with the end studs.

4. A sectional building construction for diners and the like including a plurality of separate 45 transversely disposed housing sections composed of a floor section comprising joists provided at their ends with tenons, flooring supported by the joists and side sills provided at their inner faces with mortises of greater depth than the tenons of the joists and receiving the same and extending 50 above the said tenons to the upper faces of the sills, side wall sections provided with studs having tenons at their lower ends fitted in the upper portions of the mortises of the side sills to form a foot lock for the side wall sections, and a 55 roof section supported by the side wall sections.

5. A sectional building construction for diners and the like including a plurality of separate transversely disposed housing sections composed of a floor section comprising joists provided at their ends with tenons, flooring supported by the joists and side sills provided at their inner faces with mortises of greater depth than the tenons of the joists and receiving the same and extending 65 above the said tenons to the upper faces of the sills, side wall sections provided with studs having tenons at their lower ends fitted in the upper portions of the mortises of the side sills to form a foot lock for the side wall sections, said side 70 wall sections having extensions overlapping the sills, means for securing the side wall sections to the sills to retain the studs in interlocked relation with the sills, and a roof section supported by the side wall sections.

6. A sectional building construction for diners 75

- and the like comprising a plurality of separate transversely disposed housing sections including side wall sections provided with vertical studs having tenons at their upper ends, side wall plates located at the top of the side wall sections and approximately L-shaped in cross-section and having mortises in their lower faces receiving the tenons of the side wall studs to form a head lock for the side wall sections, and a roof section having roof plates inverted L-shaped in cross-section fitting the side wall plates and interlocking the roof section with the side wall sections against movement laterally of the building construction.
7. A sectional building construction for diners and the like comprising a plurality of separate transversely disposed housing sections including side wall sections provided with vertical studs having tenons at their upper ends, side wall plates located at the top of the side wall sections and approximately L-shaped in cross-section and having mortises in their lower faces receiving the tenons of the side wall studs to form a head lock for the side wall sections, and a roof section having roof plates inverted L-shaped in cross-section fitting the side wall plates and interlocking the roof section with the side wall sections against movement laterally of the building construction, said side wall sections being provided at the top with extensions overlapping the roof plates.
- 30 8. A sectional building construction for diners and the like comprising a plurality of separate transversely disposed housing sections including side wall sections provided with vertical studs having tenons at their upper ends, side wall plates located at the top of the side wall sections and approximately L-shaped in cross-section and having mortises in their lower faces receiving the tenons of the side wall studs to form a head lock for the side wall sections, a roof section having roof plates inverted L-shaped in cross-section fitting the side wall plates and interlocking the roof section with the side wall sections against movement laterally of the building construction, said side wall sections being provided at the top with extensions overlapping the side wall plates and the roof plates, and means including lag bolts piercing the side wall plates and engaging the roof plates to tie the roof section to the side wall sections.
- 50 9. A sectional building construction for diners and the like including a plurality of separate transversely disposed housing sections composed of a floor section comprising joists provided at their ends with tenons, flooring supported by the joists and side sills provided at their inner faces with mortises of greater depth than the tenons of the joists and receiving the same and extending above the said tenons to the upper faces of the sills, side wall sections provided with vertical studs having tenons at their upper and lower ends, the lower tenons fitting in the upper portions of the mortises of the sills to form a foot lock, said side wall sections having top and bottom extensions, means for tying the side wall sections to the floor section, side wall plates approximately L-shaped in cross-section having mortises in their lower faces receiving the tenons of the upper ends of the studs to form a head lock, a roof section provided with roof plates approximately inverted L-shaped in cross-section fitting the side wall plates to interlock the roof section against lateral movement, horizontal bead strips covering the outer ends of the roof ribs, the adjacent portions of the roof plates and the outer edges of the roof covering and provided at the bottom with longitudinal recesses receiving the upper edges of the top extensions of the side wall sections.
- 55 10. A sectional building construction for diners and the like including a plurality of separate transversely disposed housing sections composed of a floor section comprising joists provided at their ends with tenons, flooring supported by the joists and side sills provided at their inner faces with mortises of greater depth than the tenons of the joists and receiving the same and extending above the said tenons to the upper faces of the sills, side wall sections including vertical studs having tenons at their upper and lower ends, the lower tenons fitting in the upper portions of the mortises of the sills to form a foot lock and an outer covering sheet secured to the side wall studs and having top and bottom extensions, means for tying the side wall sections to the floor section, side wall plates approximately L-shaped in cross-section having mortises in their lower faces receiving the tenons of the upper ends of the studs to form a head lock, a roof section provided with roof plates approximately inverted L-shaped in cross-section fitting the side wall plates to interlock the roof section against lateral movement, said roof section being composed of a roof covering and roof ribs provided at their ends with recesses located at the lower faces of the roof ribs and fitting the upper surfaces and the inner side surfaces of the roof plates, and means for tying the roof section and the side wall sections together.
- 35 11. A sectional building construction for diners and the like including a plurality of separate transversely disposed housing sections composed of a floor section comprising joists provided at their ends with tenons, flooring supported by the joists and side sills provided at their inner faces with mortises of greater depth than the tenons of the joists and receiving the same and extending above the said tenons to the upper faces of the sills, side wall sections including vertical studs having tenons at their upper and lower ends, the lower tenons fitting in the upper portions of the mortises of the sills to form a foot lock, and an outer covering sheet secured to the side wall studs and having top and bottom extensions, means for tying the side wall sections to the floor section, side wall plates approximately L-shaped in cross-section having mortises in their lower faces receiving the tenons of the upper ends of the studs to form a head lock, a roof section provided with roof plates approximately inverted L-shaped in cross-section fitting the side wall plates to interlock the roof section against lateral movement, horizontal bead strips covering the outer ends of the roof ribs, the adjacent portions of the roof plates and the outer edges of the roof covering and provided at the bottom with longitudinal recesses receiving the upper edges of the top extensions of the side wall sections.
- 40 12. A sectional diner including a plurality of transversely disposed diner sections comprising floor sections having continuous side sills, side wall sections detachably interlocked at the bottom with the floor sections and provided at the top with continuous side wall plates having longitudinal recesses, and roof sections supported by the side wall sections and having depending portions detachably interlocked with said recesses, and vertical bars extending from the floor sections to the roof sections and secured to the same and arranged at intervals throughout the length of the diner and forming a cage for tying the roof sections and floor sections firmly and securely together and for retaining the side wall sections in place whereby the side wall sections are pre-

vented from buckling, bulging, slewing over or separating from one another or from the roof and floor sections.

13. A sectional diner including a plurality of 5 transversely disposed diner sections comprising floor sections having continuous side sills, side wall sections detachably interlocked at the bottom with the floor sections and provided at the top with continuous side wall plates having longitudinal recesses, and roof sections provided with 10 roof plates having depending portions inter-

locked with the continuous side wall plates and vertical bars extending from the floor sections to the roof sections and secured to the same and arranged at intervals throughout the length of the diner and forming a cage for tying the floor and roof sections together and for retaining the side wall sections in place whereby the side wall sections are prevented from buckling, bulging, slewing over or separating from one another or from the roof and floor sections. 5
